US00D890301S

(12) **United States Design Patent** (10) **Patent No.:** **US D890,301 S**
(45) **Date of Patent:** **** Jul. 14, 2020**

(54) **VALVE**

(71) Applicant: **MINIMAX GMBH & CO. KG**, Bad Oldesloe (DE)

(72) Inventors: **Peter Kempf**, Bad Oldesloe (DE);
Frank Stachowitz, Ratzeburg (DE);
Loh Patrick, Hamburg (DE); **Volker Bechtloff**, Timmendorfer Strand (DE)

(73) Assignee: **Minimax Viking GmbH & Co. KG**, Bad Oldesloe (DE)

(**) Term: **15 Years**

(21) Appl. No.: **35/505,448**

(22) Filed: **Feb. 5, 2018**

(80) **Hague Agreement Data**

Int. Filing Date: **Feb. 5, 2018**

Int. Reg. No.: **DM/099876**

Int. Reg. Date: **Feb. 5, 2018**

Int. Reg. Pub. Date: **Aug. 10, 2018**

(30) **Foreign Application Priority Data**

Aug. 4, 2017 (DE) 40 2017 100 888

(51) **LOC (12) Cl.** **23-01**

(52) **U.S. Cl.**

USPC **D23/233**
